ROTARY COMPRESSOR FOR REFRIGERATING APPARATUS

Melvin P. Penn, Dayton, Ohio, assignor to General Motors Corporation, Dayton, Ohio, a corporation of Delaware

Application March 31, 1936, Serial No. 71,852

2 Claims. (Cl. 230—149)

This invention relates to refrigerating apparatus and more particularly to novel compressors and pumps.

Rotary pumps and compressors have been replacing reciprocating pumps and compressors to a great extent within recent years. However, this change has only taken place mainly in the small sizes. In the larger sizes of pumps and compressors, the reciprocating compressor is standard. Some attempts have been made to provide large rotary pumps and compressors, but such attempts have not been entirely successful for the reason that most rotary compressors and pumps have a rather great degree of unbalance, both static and dynamic, and particularly large unbalanced pressures on the moving parts which impose large forces upon the bearings necessitating excessively large bearings.

It is an object of my invention to combine the desirable characteristics of reciprocating pumps and rotary pumps.

It is another object of my invention to provide a rotary pump wherein the moving parts are well balanced and in which the bearing loads are small.

It is a further object of my invention to provide a pump which can be readily made in different capacities by slight changes in manufacture of one or more of the parts.

It is another object of my invention to provide an improved lubricating means and system for rotary pumps.

It is a still further object to provide an improved rotary pump having relatively great capacity and displacement for its size and weight.

It is still another object of my invention to provide a pump in which the moving parts are statically and dynamically balanced and in which the fluid pressures upon the moving parts are balanced.

Further objects and advantages of the present invention will be apparent from the following description, reference being had to the accompanying drawings, wherein a preferred form of the present invention is clearly shown.

In the drawings:

Fig. 1 is a vertical sectional view of a rotary compressor embodying my invention taken along the lines 1—1 of Fig. 2 together with a diagrammatic representation of the remainder of refrigerant air conditioning system;

Fig. 2 is a sectional view taken along the lines 2—2 of Fig. 1;

Fig. 3 is a view looking at the left side of the

compressor shown in Fig. 1 with the end casing member removed; and

Fig. 4 is a sectional view taken along the line 4 of Fig. 1.

Briefly, in this application, I have disclosed a refrigerant air conditioning system including a rotary compressor having an elliptical rotor or impeller rotatively mounted within a cylindrical casing. This cylindrical casing is provided with slots at the top and bottom receiving divider blocks which are held in engagement with the impeller by springs. The lower divider block dips into an oil reservoir and has an oil pump connected thereto which pumps oil to the rotor bearings as well as to the bearing surfaces of the upper divider block from which excess oil is conducted to the sealing surfaces of the compressor. This construction provides a symmetrical rotor and pumping chambers providing balanced fluid pressure forces upon the rotor.

Referring now to the drawings and more particularly to Fig. 1, there is shown a refrigerating system including an air conditioning cabinet 20 provided with a refrigerant evaporating means 22 and a motor driven fan 24 for drawing air from the room 26 through an inlet opening 28 in the cabinet and discharging the air through an outlet opening 30 back into the air of the room. Refrigerant within the evaporating means 22 evaporates under reduced pressure and absorbs heat from the air circulated by the motor driven fan 24. This evaporated refrigerant is withdrawn from the evaporating means 22 through a return conduit 32 which connects to the inlet of a rotary compressor 34. The rotary compressor 34 compresses the refrigerant and forwards the compressed refrigerant through a supply conduit 36 to a condenser 38 which liquefies the compressed refrigerant. This liquefied refrigerant is collected in a receiver 40 which is connected to the evaporating means 22 by a liquid conduit 42 provided with an automatic thermostatic expansion valve 44 provided with a thermostat control bulb 46 in contact with the outlet of the evaporating means 22.

The compressor is driven by an electric motor 50, either directly through a detachable coupling or as shown through pulley and belt means 52. The electric motor 50 is connected in series with a thermostatic switch means 54 exposed to the air in the room 26. The switch 54, together with the motor 50, are located in parallel electric circuit relation with the fan motor 24 and all of the elements of the electric circuit are located in series with the manual control switch 56. In

this way, the fan may be kept in operation for ventilation, regardless of the operation of the motor-compressor unit.

Referring now more particularly to the compressor, there is shown a central casting 60 having a central cylindrical wall 62 enclosing a cylindrical chamber 64. This cylindrical chamber 64 is closed at its ends by inner end plates 66 and 68 which are fastened by bolts, studs or cap screws to the faces of the central casting 60. Outer end plates 70 and 72 are likewise fastened to the central casting by bolts, studs or cap screws.

The end plates 66 and 68 are each provided with inserted bosses 74 and 76 provided with bearing bushings 78 and 80. The inserted boss 76 is closed at the end by a dished sheet metal member which is pressed into place. The bearing bushings 78 and 80 support the bearings 84 and 86 of a drive shaft 88 which extends from the bearing portion 84 through a boss and a sealing plate 90 formed in the end plate 70. A shaft seal is provided within this boss between the plate 90 and the bearing portion 84 of the shaft. This seal includes a rotatable seal ring 94 provided with a wedge shaped gasket 96 of a compound containing chloro-2-butadiene 1,3. This wedge shaped gasket 96 is held in place by a washer 98 and a compression spring 102 which tends to hold the wedge shaped gasket in relatively tight engagement with the drive shaft 88 and the seal ring 94. The rotatable seal ring 94 has a sealing surface which is held in engagement with a stationary seal ring 104 supported within a recess in the plate 90 by a resilient gasket 106 of substantially the same material as the gasket 96.

Between the bearing portions 84 and 86 of the drive shaft 88 is an enlarged portion which is provided with a rotor or impeller 108 which may have its periphery elliptical in shape. However, other forms of surfaces may be adopted, such as a constant acceleration surface which will be later explained. This rotor or impeller is placed onto the enlarged portion of the shaft and locked from rotation thereon by a pair of half round keys 110. Opposite the half round keys 110 is a key way 112 in the rotor or impeller which serves another purpose. The drive shaft 88 is held in place by sets of thrust members and washers 114 and 116 which are mounted upon the bearing portions 84 and 86 of the drive shaft and set in between the enlarged portion of the shaft and the inner faces of the inner end plates 66 and 68. The rotor 108 also has its end portions fitting against the inner faces of the end plates 66 and 68.

The housing 60 is provided with slots at the bottom and top designated by the reference characters 118 and 120. These slots receive reciprocable divider blocks 122 and 124 which are held in engagement with the peripheral surfaces of the rotor by pairs of compression type coil springs 126 and 128. These compression type coil springs extend from an inner face of the wall 65 of the central casting 60 into drilled apertures in the divider blocks. Beneath the lower divider block there is provided a passage 130 which connects with oil reservoir chambers 132 and 134, which are located on either side of the lower half 70 of the cylinder 62 and the lower divider block and which connect to the passage 130 through its end portion. Both of these oil reservoirs 132 and 134, as well as the passage 130, open into the space between the inner end plate and the outer end plate 70 which also contains the shaft

75 seal and serves as a discharge chamber 138 for the compressor. A passage 136 is provided in the central casting 60 directly above the upper divider block 124 which also communicates with the discharge chamber 138 located between the inner and outer end plates 66 and 70.

On the opposite side of the compressor between the inner and outer end plates 68 and 72, there is provided a suction or inlet chamber 140 for the compressor. For this purpose the outer end plate 72 is provided with an inlet opening 142 which connects to the return conduit 32 of the refrigerating system. The inner end wall or plate 68 is provided with upper and lower inlet openings 144 and 146, which extend from the chamber 140 into the cylindrical chamber 64 adjacent one side of the upper and lower divider blocks 124 and 122 respectively. These holes or inlet openings serve to supply the two compression chambers 148 and 150 which are formed between the small diameter portions of the elliptical surface and the inner face of the cylindrical wall 62. These compression chambers of course are not fixed as is usually the case, nor in one sense are they permanent.

In the other end plate 66 there is provided a plurality of discharge openings 152 and 154 which are located upon the opposite side of the divider blocks from the inlet ports, in addition to being located upon the other wall. These outlets are each provided with spring flapper valves 156 and 158 which control the discharge of compressed gas or fluid from the compression or pumping chambers to prevent compressed fluid from returning from the discharge chamber into the compression chamber. The outlet from the discharge chamber 138 is provided by a threaded opening 160 which connects with the supply conduit 36 connected to the condenser 38.

The rotor or impeller 108 is shown as having a periphery in the form of a true ellipse having its major axis substantially equal to the diameter of the inner cylindrical face of the wall 62. The amount of clearance provided between the major diameter of the rotor and the inner cylindrical surface is preferably between 0.0005 and 0.001 of an inch. However, a slightly greater amount of clearance may be used in many cases depending upon the fluid pumped and the lubricant used. The minor axis may be reduced or enlarged as desired to increase or decrease the capacity of the compressor. Incidentally, this forms a very convenient means for providing compressors of different capacities without changing their external dimensions or any of the parts excepting the rotor or impeller. This is an extremely important advantage in the larger sizes of compressors since the production upon these sizes is relatively low and the cost of providing tools is relatively great. Therefore, by making it possible to use the same parts for a number of different sizes of compressors, a considerable saving in manufacturing costs is thus made possible. Of course, it is also possible to change the capacity by varying the speed of the compressor or the length or diameter of the cylinder.

The rotor or impeller is preferably made of some form of alloy steel such as nitalloy or mianite and has its outer surfaces case hardened and ground. In addition, the outer surfaces may, if desired, be plated with chromium or other plating capable of forming an excellent wearing surface.

The inner side plates, as well as the divider

blocks, may also be made of a similar material or a material capable of providing a good wearing surface together with such a material. Preferably, the divider blocks are made of a slightly 5 softer material than the rotor or impeller so that the rotor or impeller will have as little wear as possible due to the sliding contacts of the divider block with its surface. However, since the pressure of the divider blocks upon the rotor 10 is small, the wear will naturally be very small.

Instead of an elliptical periphery, the rotor may have a surface which provides constant acceleration and deceleration to the divider blocks so that the force that it is necessary to employ 15 to hold the divider blocks in contact with the periphery of the rotor may be made as small as possible. Such a constant acceleration periphery may have its minor axes varied in a similar manner to the elliptical contour in order to provide 20 different capacities.

The lower divider block 122 operates in a bath of lubricant designated by the reference character 162 which fills the lower portions of the oil reservoirs 132 and 134, as well as the lower 25 portion of the discharge chamber 138 and the passage 130 beneath the divider block. This lower divider block 122 is therefore provided with an ample supply of lubricant. The movement of this divider block, however, also serves to actuate an oil pump which supplies oil under pressure to the bearings of the drive shaft 88 as well as to the passage 136 provided directly above the upper divider block 124 for providing direct lubrication to this upper divider block.

35 The piston 164 of this oil pump is provided with a flange at one end which is clamped to the outer end of the divider block by a plate 166 provided with a recessed portion containing an opening which receives the flanged end of the piston 164. This plate is fastened to the outer surface of the lower divider block by a plurality of screws located upon opposite sides of the piston 164. The piston is received within a cylinder formed in the upper end of the threaded plug 40 168 provided with a hex head. This threaded plug is threaded into the bottom of the central casting from beneath and has an inlet part 170 in one wall which opens into a cut away portion 172 for feeding the oil from the passage 130 45 into the cylinder. This inlet opening is of the port type and permits oil to flow into the cylinder when the lower divider block and the piston moves upwardly to their uppermost positions.

50 At the bottom of the cylinder outlets on both sides are provided which are connected by a pair of passages 174 to a pair of inserts 178 and 180, each provided with ball type check valves which act as discharge valves for the oil pump. One of these check valves is connected by a passage and 55 a tubular connection 182 with the bearing bushing 80 and the bearing 86. The oil supplied through this tubular connection 182 spreads itself around the bearing in both directions and the portion leaking from the end of the bearing is 60 conducted through a passage 184 to a chamber formed in the side thrust washer or member 116, which washer is provided with an aperture leading to the passage 112. The above mentioned chamber also receives excess lubricant from the 65 other end of the bearing 86. The lubricant passes through this passage 112 to the chamber surrounding the thrust washer or member 114 which is also provided with an aperture leading to a chamber formed in the thrust member directly at the face of the bearing bushing so that lubri-

cant may flow through the bearing 84 from one end to the other and be discharged in the discharge chamber 138.

The other tubular connection 186 leads to an oil passage 188 in the upper portion of the side 5 plate 68 from which the fluid is discharged into the chamber 136 directly above the divider block 124. This lubricant, therefore, provides an adequate supply of lubricant for the upper divider block. From this chamber 136 the lubricant 10 flows through a cut 190 made in the side plate 66 into a trough 192 which conducts this lubricant to a collecting basin 194 from which the lubricant by gravity passes through an oil passage 196 to a point over the shaft sealing ring 94 so that the shaft seal will be provided with an adequate supply of lubricant. The side portions of the rotor will be lubricated by lubricant which is thrown out by centrifugal force from the chambers formed in the rotor to receive the thrust members. The periphery of the rotor may receive lubricant from that which lubricates its side faces and from the lubricant which lubricates the divider blocks. The oil or lubricant reservoir is located upon the discharge side of the compressor so that only several pounds more than discharge pressure is required to circulate the lubricant to all parts of the compressor. By providing a lubricant reservoir upon the discharge side of the compressor, lubricating difficulties peculiar to refrigerating systems are avoided to a great extent.

In operation, evaporated refrigerant passes into the chamber 140 between the inner and outer end plates 68 and 72 through the inlet opening 142 and thence passes into the cylinder through the inlet openings 144 and 146, during the suction strokes of the compressor. The suction strokes begin whenever the major axis of the rotor passes each of these inlet parts 144 and 146 and each suction stroke continues until the rotor has 40 turned exactly 180°. At the same time the gas already drawn into the cylinder in the two spaces between the inner wall of the cylinder and the flattened portions of the rotor is trapped between noses or lobes of the rotor and the divider blocks. 45 Further movement of the rotor raises the pressure of this trapped gas or liquid and forces this trapped gas or liquid out through the discharge openings 152 and 154 which are controlled by the flapper valve 156 and 158. This places the compressed liquid or gas in the chamber 138 from which it escapes through the threaded outlet opening 160 which connects to the supply conduit 35 50 55 60 65 70 75 80 85 90 95 100 105 110 115 120 125 130 135 140 145 150 155 160 165 170 175 180 185 190 195 200 205 210 215 220 225 230 235 240 245 250 255 260 265 270 275 280 285 290 295 300 305 310 315 320 325 330 335 340 345 350 355 360 365 370 375 380 385 390 395 400 405 410 415 420 425 430 435 440 445 450 455 460 465 470 475 480 485 490 495 500 505 510 515 520 525 530 535 540 545 550 555 560 565 570 575 580 585 590 595 600 605 610 615 620 625 630 635 640 645 650 655 660 665 670 675 680 685 690 695 700 705 710 715 720 725 730 735 740 745 750 755 760 765 770

As mentioned before the reciprocation of the lower divider block operates the piston 164 in the cylinder formed as a part of plug 168. This plug is provided with discharge openings connected by 65 passages 174 to a plurality of check valves which in turn are connected by tubular connections and passages with the bearings of the drive shaft and the upper divider block.

It should be noted that the rotating parts are entirely symmetrical excepting for the two half 70 round keys 110 which might also be placed on the opposite side if desired. However, the weight of these keys is rather insignificant as compared to the weight of the rotor. All the rotating parts may be said to be statical and dynamically bal- 75

anced, thus providing a unit which may operate at rather high speed without appreciable vibration. The divider blocks operate in exactly the opposite directions at exactly the same speed so that these plugs which are substantially the same in weight are substantially dynamically balanced. The piston of the oil pump and its connecting plate and screws are insignificant in weight as compared to the weight of the divider blocks and the mass of the compressor. However, if it is desired to correct for this additional weight the lower divider block may be drilled in order to reduce its weight a corresponding amount. Likewise, the rotor may be drilled on the side adjacent the half round keys an amount equal to the weight of keys, or similar keys may be placed in the passage 112 and another passage provided for lubricant. Thus, unbalance tending to promote vibration is almost entirely eliminated.

20 A more important feature of this pump, however, is the fact that the forces upon the rotor are balanced. The rotor 108 is perfectly symmetrical and has opposite fluid forces upon opposite sides of all planes passing through its axis.

25 Likewise, the force of the divider blocks upon the rotor balance against each other. This makes it possible to make the bearings of the drive shaft comparatively small. This is of a great advantage in large rotary compressors and has solved one of the most perplexing problems in this type and size of compressor. This compressor is intended to operate at a motor speed of 1750 to 1800 R. P. M. However, it may also be operated at other speeds.

30 35 While this pump is particularly intended to be used for pumping gases in a refrigerating system, it may also be used for pumping either gases or liquids in other forms of apparatus with little or no modification except whatever is necessary to avoid contamination of the lubricant. This type of pump is much smaller and simpler than the conventional large size reciprocating pump

and is readily applicable to all sizes, particularly to sizes of compressors of $\frac{1}{2}$ ton up to ten tons and more refrigeration capacity.

While the form of embodiment of the invention as herein disclosed, constitutes a preferred form, it is to be understood that other forms might be adopted, all coming within the scope of the claims which follow.

What is claimed is as follows:

1. A rotary compressor having a casing provided with a rotor and a plurality of divider blocks extending into contact with the rotor positioned in slots in the wall of the casing, said slots being located in the top and bottom of the casing, a drive shaft for said rotor extending outside the said casing through an aperture in the casing, a shaft seal for said drive shaft to prevent the escape of fluid from the casing, said casing being provided with lubricant confining walls above the upper divider block and below the lower divider block, and means for taking lubricant from the slot beneath the lower divider block and discharging the lubricant upon the upper divider block, and means for discharging the surplus lubricant from the upper divider block upon the shaft seal for lubricating the shaft seal. 10 15 20 25

2. A rotary compressor having a casing provided with a rotor and a plurality of divider blocks extending into contact with the rotor positioned in slots in the wall of the casing, said slots being located in the top and bottom of the casing, said casing being provided with lubricant confining walls above the upper divider block and below the lower divider block, means for taking lubricant from beneath the lower divider block 30 and discharging the lubricant upon the upper divider block, said compressor being provided with an rotor shaft and a bearing surface outside the rotor chamber surrounding the rotor shaft, and means for conducting lubricant from said upper 35 40 divider block to said bearing surface.

MELVIN P. PENN.
